UNITED STATES PATENT OFFICE.

HUBERT F. KRANTZ, OF BROOKLYN, NEW YORK.

SWITCHBOARD.

1,248,415.

Specification of Letters Patent. Patented Nov. 27, 1917.

Application filed March 13, 1915, Serial No. 14,130. Renewed April 11, 1916. Serial No. 90,519.

To all whom it may concern:

Be it known that I, HUBERT F. KRANTZ, a citizen of the United States, and residing at Brooklyn, in the county of Kings and State of New York, have invented a new and Improved Switchboard, of which the following specification is a full disclosure.

This invention relates to a switch board.

The object of the invention is to provide a switch board having the various elements thereof so arranged that a maximum number of switch controlled connections may be safely made in a minimum of space and in a simple, efficient and practical manner.

15 A further object is to provide a switch board as above in which ready and convenient access is given to the various branch line connections and other parts.

20 A further object is to provide a switch board in which the branch line wires, which lead to the branch line connections, are securely protected and shielded from view in a manner to protect the wires against injury and to protect an operator from any injury 25 which might result from contact with the wires.

A further object is to provide a switch board in which the various switch elements, main line and branch line connections are 30 contained within a protecting compartment and in which the branch line wires, leading to the various branch line connections, are conveyed to said branch line connections by means of tube-like housings which traverse 35 the compartment and carry the branch line connections in insulated relation to the main line connections.

40 A further object is to provide a switch board as above in which a series of branch line connection supporting members extend transversely of and spaced from a series of bus bars, to the end that switch mechanisms arranged tandemwise along the bus bars may be made to connect any one or more of the 45 bus bars with a selected one or more of the overlying branch line connections.

A further object is to so arrange the parts above referred to as to coöperate with switch mechanisms which may be controlled, manually or otherwise, from the front face of 50 the board.

A further object is to provide main bus bars and auxiliary bus bars in a novel relation, and to provide means whereby the aux-

iliary bus bars may be electrically disconnected from the main bus bars by a novel arrangement of switch mechanism. 55

Other objects will be in part obvious from the annexed drawings and in part indicated in connection therewith by the following 60 analysis of this invention.

The switch instrumentality herein shown is claimed in a divisional application filed February 12, 1916, Serial No. 77,878.

This invention accordingly consists in the 65 features of construction, combinations of parts, and in the unique relations of the members and in the relative proportioning and disposition thereof; all as more completely outlined herein. 70

To enable others skilled in the art so fully to comprehend the underlying features thereof that they may embody the same by the numerous modifications in structure and relation contemplated by this invention, 75 drawings depicting a preferred form have been annexed as a part of this disclosure, and in such drawings, like characters of reference denote corresponding parts throughout all the views of which:— 80

Figure 1 is a perspective of the rear side of a panel board embodying this invention, showing the arrangement of the various bus bars and showing the branch-line housing unit, together with the quick-break switches 85 operating in direct contact with the bus bars, etc.

Fig. 2 is a detail showing the use of a replaceable wear plate forming a component part of a bus bar for taking up the disintegrating tendency of the spark. 90

Fig. 3 is a detail of a contact terminal adapted to be contacted directly by a brush of the switch.

Fig. 4 is a horizontal section taken through line 4—4 of Fig. 5.

Fig. 5 is a plain rear elevation of the panel board.

Fig. 6 is a plan partly in section and enlarged showing certain details of a toggle 100 operated switch.

Fig. 7 is a front elevation showing the handles for operating the switch.

Fig. 8 is a side elevation showing in full lines the handle in the toggle-erecting position and showing it in dotted lines in the toggle-breaking position. 105

Fig. 9 is a detailed inside elevation of the

construction of a conduit for receiving the branch-line wires.

Continuing now, by way of a more detailed analysis of the primary characteristics of this invention, A designates a board of insulating material, as of slate, marble or the like, which forms the front exposed face of the panel carrying the operating handles and on the rear side of which are mounted 10 the various connections arranged in accordance with this invention. B designates a strip of insulating material which will ordinarily be arranged at an angle with the front face A and which may be utilized to 15 carry the bus bars X, Y, Z receiving current directly from the mains. Various branch-line circuits are to be supplied with current derived from these main bus bars. The branch line circuits are connected to the 20 main bus bars preferably through the medium of auxiliary bus bars and these auxiliary bus bars, as x y and z and x' and y' may be connected with the main bus bars either permanently as shown with respect 25 to the auxiliary bus bars x' and y' or by a switch mechanism as shown with respect to the auxiliary bus bars x y and z . This invention proposes a very simple and direct manner of accomplishing the latter purpose, by mounting the auxiliary bus bars x , 30 y , z on the rear face of the board A in such a way that a switch blade or brush may extend diagonally through the corner space and contact at its ends with one of the auxiliary bus bars and with a terminal of one 35 of the main bus bars.

Preferably, a terminal contact piece 1, 2, 40 3 will be provided for each of the main bus bars and these terminals are each arranged equidistant from the board A. Each terminal piece may be composed of an angle member attached to the board B by means of the foot 4 and providing a clip 5 for receiving the contact end of a fuse 6. The 45 contacting face of this angle member may carry a replaceable plate 7 so that when its surface becomes roughened by frequent use of the switch it may easily be substituted by another. The opposite terminal of the fuse 50 6 is received by a clip 8 extending from the extension 9 that is connected at its upper end to the bus bar. The construction in the case of the contact pieces 2 and 3 is similar, save for the fact that the extension 10, etc., 55 will vary in length in accordance with the distance of the respective main bus bars. The auxiliary bus bar x is secured to the rear face of the board A in the same horizontal plane as the contact 1 so that its end 60 terminates diagonally opposite said contact and said end may carry a replaceable facing 11 similar to that indicated by 7. The auxiliary bus bars y , z , etc., are arranged in a similar manner.

In the event that it is unnecessary to use a main switch between the main bus bars and the auxiliary bus bars, the switch mechanism C may be omitted, and a direct connection be established between the two as shown in the lower portion of Fig. 1. 70

Thus, the ends of the auxiliary bus bars x' and y' will terminate as indicated by 12 and 13 closely adjacent the side board B that carries the main bus bars, and extensions 14 and 15 of suitable length will extend from the appropriate bus bars and terminate equi-distant from the front board A. This construction enables duplicate brace connectors 16 and 17 to be used for the purpose of permanently establishing connection 80 between the bus bars Y and Z and the auxiliary bus bars x' and y' .

The main switch C is preferably constructed of the double-break type in which the switch blades are pivotally mounted intermediate their ends and are adapted to swing into and out of circuit closing position. In the drawings the switch C is provided with three independent blades as G, G' and G'' one for each of the auxiliary bus bars x , y and z . These are held spaced apart in proper insulated relation and in co-operative relation with the adjacent main and auxiliary bus bars by means of insulating and supporting members 22, 23 and 24 the 90 opposite ends of which are pivotally supported as at 26 and 27. A bracket 29 which supports the end 26 may support also suitable mechanism by means of which the blades may be shifted into and out of circuit closing position through the medium of an operating handle I mounted at the opposite side of the front board A and being connected with the switch blades by a link H which extends through a suitable aperture in the front board. 100

It is proposed to locate a main switch C, adjacent the corner formed by the intersection of the planes of the main bus bars and of the auxiliary bus bars so that the axis of rotation of the main switch C will be parallel with the intersection of the two planes. As shown by Fig. 1, the main bus bars extend parallel to said intersection and the auxiliary bus bars extend transversely to said intersection, and the terminals of these respective bus bars are preferably arranged diagonally opposite one another, as shown by Fig. 1. This arrangement effects many important economies in the amount of metal and the number of parts required. 110

In the illustrated embodiment, the blades G swing in a plane transverse to the intersection between the planes A and B, and when occupying a diagonal position they may establish an electrical connection between the parts. 120

It will be noted that this arrangement is

equally applicable to two-wire or three-wire systems and the necessary width of the slate or marble board A is but little increased by the utilization of a main supply switch, 5 such as indicated by C.

A simplified system and construction for the branch-line circuits is also provided by this invention. The various branch-line wires J, which are provided with insulation 10 in the ordinary manner, extend upwardly or downwardly, as the case may be, along one side of the narrow insulating board E and are connected to suitable terminals 35. These terminals are arranged in alinement 15 on one side of the narrow board E, as shown best by Fig. 1, and the branch-line wires J preferably are located on the opposite side and pass through apertures 36 to contact directly with the terminals 35. These terminals 20 preferably are provided with fuse-receiving clips 37 adapted to make contact with the terminals of the fuses 38 or 39, whereby the current may be received from the contact making terminals 40 of the type 25 shown by Fig. 3, and with which the blades K, K' and K'', of the branch line switches D and F directly contact, as shown by Fig. 1. These terminals 40 may be made alike, thus introducing economies in manufacturing, 30 and they are arranged in alinement as shown and may have replaceable facings 41, as shown by Fig. 3, so that the switch blades may contact directly with said terminals and the actual contact surfaces may be renewed in case of excessive pitting. The narrow 35 board E extends transversely to the bus bars x, y and z and preferably inclines somewhat to the plane thereof, so as to expose the fuse-bearing side thereof and thereby facilitate the replacement of fuses. An 40 advantageous construction for the mounting of these boards is shown best, perhaps, by Fig. 5. The upper and lower partitions L and M extend transversely to the plane of 45 the board A and in conjunction with the plates L' and M' form gutters or passageways N open at their ends to receive the main line wires which may enter through insulated bushings 42 and be connected to 50 the main bus bars X, Y and Z. These gutters N also carry the branch-line wires J and said branch line wires extend inwardly through openings at 43 adjacent each of the narrow terminal bearing boards E, E', etc. 55 These boards each preferably form the front wall of a narrow elongated box made of oppositely arranged T-irons 44 and 45 bolted at their respective ends to the plates L and M by means of angle pieces 46. An 60 L-shaped strip 47 (see Fig. 6) is secured to the T-iron 45 which is positioned nearest the board A so as to provide an overhanging lip 48. A closure or cover plate 50 has a flange 51 along one edge for engaging the

outer T-iron 44. The opposite longitudinal 65 edge of this plate engages against the inner surface of the over-hanging lip 48 and thereby completes the box. These parts may be assembled before the branch line wires are connected but preferably the cover plate 50 70 is omitted until the branch line wires are threaded in place. By this means a wide open and convenient space is provided for the operation of threading the wires, and after the wires have been fully threaded the 75 cover plate is then fixed into position. This is done simply by introducing one edge of the plate behind the lip 48 and by thereafter fixing the flange 51 to the angular iron 44 by suitable screws or other means. When the 80 cover plate is in position the wires are entirely concealed, the terminal boards and the parts 44, 45, 47, and 50 constituting tubular conductor carriers through which the branch line conductors extend from the 85 gutters N to their respective branch line terminals. In this way, all the wires are compacted into a relatively small space and are very effectively protected, and the entire rear side of the panel board is free from any 90 exposed wires so that it has a very clean-cut appearance. As indicated by Figs. 4 and 5, a series of similar boxes E, E', etc., preferably arranged in echelon, will be provided.

It will accordingly be perceived that I 95 have devised a simple, durable, efficient switch instrumentality which requires but few parts in its construction and which demands a comparatively small amount of copper or other valuable materials and which, 100 nevertheless, provides for a great number of branch lines within a relatively small space.

Without further analysis, the foregoing will so fully reveal the gist of this invention that others can by applying current 105 knowledge readily adapt it for various applications without omitting certain features that, from the standpoint of the prior art, fairly constitute essential characteristics of the generic or specific aspects of this invention, and therefore such adaptations should and are intended to be comprehended within the meaning and range of equivalency of the following claims.

Having thus revealed this invention, I 115 claim as new and desire to secure the following combinations of elements, or equivalents thereof, by Letters Patent of the United States:

1. An electrical switch instrumentality 120 combining a series of bus-bars arranged substantially in the same plane; a number of narrow elongated boxes extending transversely to said bus-bars at one side thereof; a series of terminals mounted on one face of 125 each box; wires positioned longitudinally in each of said boxes and connected with said terminals; and switches arranged to estab-

lish electrical connection between said terminals and said bus-bars.

2. An electrical switch instrumentality combining a board of insulating material; a partition arranged transversely thereto and forming the side of a gutter; a narrow elongated box extending from said partition parallel with said board and having a number of terminals on a face thereof; a number of wires arranged in said gutter and extending into said box through an aperture in said partition and connecting with said terminals; a plurality of bus-bars arranged parallel with said board and transversely to said box; and switch blades for establishing electrical connection between said terminals and said bus-bars.

3. An electrical switch instrumentality combining a board of insulating material; a plurality of bus-bars mounted on the rear face thereof; a partition extending transversely to the rear face thereof and forming a side of a conduit for branch-line wires and having a series of openings; a series of elongated conduits registering at their ends with said openings and extending parallel with the rear side of said board and transversely to said bus-bars and having terminals; branch-line wires extending through said openings into said conduits and connected with said terminals; switch blades adapted to establish connection between said terminals and said bus-bars; and means for operating said switches from the front side of said board.

4. An electrical switch instrumentality combining a series of parallel auxiliary bus-bars arranged in the same plane; a series of main bus-bars extending transversely to said auxiliary bus-bars and arranged in a plane at an angle to said first-mentioned plane; a series of branch-line terminals arranged in a plane at an angle with said first-mentioned plane; a series of switch-blades extending from said terminals to said auxiliary bus-bars; and a plurality of branch-line wires connecting with said terminals.

5. A switch-board combining a base-board; a plurality of parallel strips of insulating material inclined at an acute angle to said base-board; a plurality of parallel bus-bars extending transversely to said strips between the same and said base-board; a plurality of branch-line terminals arranged adjacent corresponding edges of said strips in proximity with said bus-bars; and pivotally mounted switch blades adapted to establish connection between said terminals and said bus-bars.

6. A switch-board combining a base-board; a plurality of parallel strips of insulating material spaced apart and disposed edgewise to said base-board and distanced therefrom; a series of parallel bus-bars extending intermediate the ends of the strips

between said base-board and said strips 65 transversely thereto; branch-line terminals mounted on said strips; and resilient switch-blades pivoted to swing into positions establishing electrical connection between their respective branch-line terminals and 70 said bus-bars.

7. A switch-board combining a base-board; a plurality of parallel strips of insulating material spaced apart adjacent said base-board; an elongated conductor extending transversely to said strips between the same and said base-board; branch line terminals mounted at the edge of said strips adjacent said conductor; and a resilient switch blade pivoted to swing into engagement with its respective branch-line terminal.

8. A switch-board combining a base-board; a narrow elongated strip of insulating material arranged adjacent one face of 85 said base-board but spaced away therefrom; a plurality of narrow elongated parallel conductors extending flatwise along the face of said base-board between the same and said strips and transversely thereto; a corresponding number of branch-line terminals, each arranged on said strip adjacent its respective conductor; and a corresponding number of resilient laminated switch blades pivotally mounted so as to be movable into 95 a position and contacting directly with said conductor and its appropriate branch-line terminal.

9. A switch-board combining a base-board; a plurality of parallel strips of insulating material arranged adjacent one face thereof; a plurality of narrow elongated bus-bars arranged flatwise adjacent the face of said board and extending transversely to said strips intermediate the ends of the strips and between the same and said board; a plurality of branch-line terminals carried by said strips; and a corresponding number of switches adapted to connect said terminals with said bus-bars.

10. A switch-board combining a plurality of elongated strips of insulating material spaced apart in parallelism so as to be arranged in echelon; a number of branch-line cables extending along the rear face of each strip; a number of branch-line terminals carried by the front face of each strip and connected across the plane of each strip with its appropriate branch-line conductor; a main bus-bar extending transversely to 115 said strips; and switches adapted to establish connection between said bus-bar and said branch-line terminals.

11. A switch-board combining a base-board; a plurality of parallel strips of insulating material arranged at acute angles to said base-board; a plurality of parallel bus-bars extending transversely to said

strips between the same and said base-board; a plurality of branch-line terminals arranged adjacent corresponding edges of said strips in proximity with said bus-bars; 5 and pivotally mounted switch blades adapted to establish connection between said terminals and said bus-bars.

12. A switch-board combining a base-board; a plurality of parallel strips of insulating material spaced apart in echelon adjacent said base-board; an elongated conductor extending transversely to said strips between the same and said base-board; branch-line terminals mounted at the edge 15 of said strips adjacent said conductor; and a switch-blade pivoted at an intermediate point and adapted to swing to bring its one end into contact with said conductor and its other end into contact with its respective branch-line terminal.

13. A switch-board combining a base-board, a partition carried at one face of the base-board defining a switch carrying portion at one side of the partition and a branch 25 line wire gutter at the other side of the partition, a plurality of main line contacts and branch line contacts arranged within the switch carrying portion, switch blades movable for making and breaking engagement 30 between said main line contacts and said branch line contacts, a tubular conductor carrier communicating with an opening in said partition, and extending from said partition to said branch line contacts serving 35 as a support for said branch line contacts and being adapted to carry the branch line wires therethrough from said gutter through the opening in said partition into electrical connection with said branch line 40 contacts.

14. A switch-board combining a base-board, a partition carried at one face of the base-board defining a switch carrying portion at one side of the partition and a branch line 45 wire gutter at the other side of the partition, a plurality of main line contacts and branch line contacts arranged within the switch carrying portion, switch blades movable for making and breaking engagement between 50 said main line contacts and said branch line contacts, a carrier extending from said partition to said branch line contacts, said carrier comprising a flat strip of insulating material to which said branch line contacts are 55 fixed in a row at spaced points away from said partition, said carrier comprising also means fixed to said strip of insulating material to constitute a tubular inclosure of which the strip of insulating material forms 60 one wall, said tubular inclosure communicating at its end with the opening in said partition adapted to receive branch line wires extending from the gutter inwardly through the opening in the partition and along the

tubular inclosure to said branch line contacts. 65

15. In a dead face switch-board, the combination with a base board of insulating material and a pair of bus-bars extending in substantially parallel relation along the rear 70 surface of said board adapted for carrying the opposite sides of an electric circuit, of branch-line contacts also at the rear of the board one for each of said bus bars and being spaced therefrom, switch blades also at 75 the rear of the board one for each of said bus bars, means operable from the front of the board for moving said switch blades, supporting means for the switch blades insulating said switch blades from each other 80 and holding them to move in unison for making and breaking contact between said bus bars and the respective adjacent branch line contacts, and branch line wires also at the rear of the board extending transversely 85 of and across said bus bars in insulated relation thereto and being connected with said branch line contacts.

16. A dead face switch-board combining a series of bus bars arranged in substantially 90 parallel relation along the rear surface of the switch-board, branch line terminals also at the rear of the board one for each of said bus bars, switch blades also arranged at the rear of the board one for each of said bus 95 bars, means operable from the front of the board for moving said switch blades to make and break contact between said bus bars and the respective adjacent branch line terminals, and branch-line wires also at the rear 100 of the board extending transversely and across the bus bars in insulated relation thereto and being connected with said branch line terminals.

17. A dead face switch-board combining a 105 series of bus bars arranged in substantially parallel relation along the rear surface of the switch-board, means defining a branch line wire gutter also at the rear of the board extending substantially parallel with said bus bars, branch-line terminals also at the rear of the board one adjacent each of said bus-bars, switch blades also arranged at the rear of the board one for each of said bus bars, means operable from the front of the 110 board for moving said switch blades to make and break contact between said bus bars and the respective adjacent branch-line terminals, and branch line wires also at the rear 115 of the board extending longitudinally along said gutter and thence laterally from the gutter transversely of and across the bus bars in insulated relation to the bus bars and into electrical connection with said branch-line terminals.

18. A switch-board combining a series of bus bars extending side by side along one side of the switch board, branch line termi- 125

- nals also at the same side of the board one for each bus bar, switch blades also arranged at the same side of the board one for each bus bar, means for operating the switch 5 blades to make and break contact between said bus bars and the respective adjacent branch line terminals, a branch-line-wire-supporting member arranged at the same side of the switch-board and extending 10 transversely of and across the bus-bars, and branch-line wires extending along said supporting member transversely of the bus-bars and into connection with said branch-line terminals.
- 15 19. A switch board combining a base board; a strip of insulating material disposed edgewise to said base board; a series
- of parallel bus-bars supported by said base board and extending in a direction transverse to said strip, terminals mounted on 20 said strip and positioned in planes other than those occupied by said bus-bars and the base board, branch line wires extending longitudinally of, and carried on, said strip, and switch blades for establishing electrical 25 connections between said terminals and said bus-bars.

In witness whereof, I hereunto subscribe my name, as attested by the two subscribing witnesses.

HUBERT F. KRANTZ.
